(57) **CLAIM**

The ornamental design for an elevated laptop stand with cooling fan, as shown and described.

DESCRIPTION

FIG. 1 is a perspective view of the elevated laptop stand with cooling fan showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and,

FIG. 10 is a partial enlarged view of portion 10 in FIG. 2.

The broken lines shown in the drawings represent portions of the elevated laptop stand with cooling fan that form no part of the claimed design. The dot-dash lines shown in the drawings indicate the portion that is shown enlarged.
